UNITED STATES PATENT OFFICE.

JOHN SWEGLES, OF WAYNE, MICHIGAN.

HANDLE FOR BAGS.

SPECIFICATION forming part of Letters Patent No. 499,481, dated June 18, 1893.

Application filed April 25, 1892. Serial No. 430,565. (No model.)

To all whom it may concern:

Be it known that I, JOHN SWEGLES, a citizen of the United States, residing at Wayne, in the county of Wayne and State of Michigan, 5 have invented certain new and useful Improvements in Handles for Bags, of which the following is a specification, reference being had therein to the accompanying drawings.

This invention relates to new and useful 10 improvements in bags, and the invention consists in the peculiar construction of a handle applied to the lower end of a bag and further in the peculiar manner of fastening or clamping the handle by forming an enlargement at 15 the base of the bag and forming corresponding recesses in a rigid block adapted to be secured exteriorly of the bag, and further in the peculiar construction, arrangement and combination of the various parts, all as more fully 20 hereinafter described.

In the drawings, Figure 1 is a side elevation of a bag, showing my handle applied to the lower end thereof. Fig. 2 is a perspective view of the various parts of the handle. Fig. 25 3 is a cross section on line $x-x$, in Fig. 1. Figs. 4 and 5 are similar sections showing modified forms of construction. Fig. 6 is a longitudinal section on line $y-y$ in Fig. 3.

It is well known in handling bags filled with 30 grain and other similar material that it is impossible to get any convenient hold at the lower end of the bag and to overcome this difficulty I have connected to the lower end of the bag a handle, preferably so constructed 35 that it may be clamped exteriorly upon the bag without the necessity of putting any bolts or screws through the material of the bag itself and so constructed that it may be attached to any bag.

40 A is an ordinary grain bag showing the top gathered in and tied with a string in the ordinary manner and at the bottom in Fig. 1, I have shown my handle attached.

The handle consists of a rigid block clamped 45 upon the bag and preferably centrally at the lower end and is composed of the cylindrical body B having tapering ends provided with a groove C on its upper face and a recess D in the bottom of the groove. The groove C 50 is preferably of substantially dovetail shape and E is a block corresponding in shape to the groove C adapted to fit therein with suffi-

cient looseness to allow the thickness of the bag beside the block.

F is a strip or block adapted to be placed 55 inside the bag at the point where the handle is secured and at a point where it will enter the recess D in the bottom of the handle, being placed therein, as shown in Fig. 3. The securing block E is then forced in longitudinally and tightly clamps the strip F in its recess and clamps the bag tightly between it and the handle, as plainly shown in the drawings. This block may then be secured in position by a screw G or the slots of the groove 60 C may be glued, or it may be secured in any other desired manner. The handle thus attached to the bottom of the bag, forms not only a convenient means for lifting the bag, but also in dragging it along the floor it takes 70 the wear and prevents the wearing and tearing of the bag.

It will be impossible to draw the bag out of the handle unless the bag is either torn or sufficient strain is put upon it to split the handle, which in practice I find is seldom done. 75

In place of making the groove in the body of the handle, I may cut out a section of a securing block making a groove therein, as shown in Fig. 5, in which the body B is provided with an aperture H, preferably slightly to one side and the longitudinal slot I extends from the exterior of the block into the aperture. The securing strip or block F is then inserted into the bag and forced longitudinally into the aperture H, this block being provided with a notch J in which a securing pin K is adapted to engage, preventing longitudinal movement. 85

What I claim as my invention is— 90

1. In a bag, a handle consisting of an outer member, arranged on the out side of the bag and an interlocking inner member in combination with the bag and means for securing the outer and inner members together, substantially as described. 95

2. In a bag, the combination with a flexible portion thereof, of a grooved hand block on the out side of the flexible portion, a block within said flexible portion and removable means for securing the inner block and flexible portion in the hand block, substantially as described. 100

3. In a bag, the combination with an outer

handle having a recess therein, into which a section of the bag is fitted, of a removable block fitted in said recess over the inclosed section and outside the bag, and means within the inclosed section for locking the same between the handle and block substantially as described.

4. In a flexible bag, the combination with the base thereof, of a grooved handle block fitted to the base, and a block outside the bag, fitted into the groove, of the handle and onto the material of the base, substantially as described.

5. In a bag, the combination with a grooved hand block in which a portion of the bag is fitted, of a block within the bag fitted in the groove and an exterior block in the groove

above the other block, substantially as described.

6. In a bag, the combination of a hand block, having a dovetail groove therein in which a portion of the bag is fitted and a block outside of the bag, fitted in the groove, substantially as described.

7. In a grain bag, the combination with a portion of the same, of an adjustable handle removably secured to said portion, substantially as described.

In testimony whereof I affix my signature in presence of two witnesses.

JOHN SWEGLES.
